Inventor.

Jacob L. Brallier,
By his Attorney,
Horace Pettit.

UNITED STATES PATENT OFFICE.

JACOB L. BRALLIER, OF PHILADELPHIA, PENNSYLVANIA, ASSIGNOR, BY DIRECT AND MESNE ASSIGNMENTS, TO HIMSELF AND WILLIAM CAMPBELL, OF SAME PLACE.

NECKTIE-FASTENER.

SPECIFICATION forming part of Letters Patent No. 398,696, dated February 26, 1889.

Application filed November 9, 1888. Serial No. 290,355. (No model.)

To all whom it may concern:

Be it known that I, JACOB L. BRALLIER, of the city of Philadelphia, and State of Pennsylvania, have invented a certain new and 5 useful Improvement in Strap-Fasteners; and I do hereby declare the following to be a full, clear, and exact description thereof, reference being had to the accompanying drawings, forming part of this specification.

10 My invention has relation principally to fasteners for securing the loose end of the band of a necktie or scarf after it has passed around the neck to the tie or scarf and holding it in proper position; and it consists in a 15 small metal frame or casing open at the upper and lower ends and sewed or otherwise secured to the inner side of the tie or scarf. To the lower opening of the casing is hinged a tongue or clamp, which, when the tie end is 20 passed through the frame or casing, is pushed down and brought to bear against the tie end and retained in that position by means of a spring-plate provided in the frame, and thereby prevents the tie end or scarf from slipping.

25 The object of my invention is to provide a fastener which will rigidly hold the strap or band well in position, and which at the same time can be fastened or released by a single 30 simple movement of the tongue or clamp.

A further object is to provide a fastener which shall be free from pins or springs, and thereby prevent the wearing out and fraying of the tie end by the constant puncturing, 35 and at the same time prevent the pricking of the fingers, which constantly occurs in adjusting the strap where pins are employed.

In the accompanying drawings, Figure 1 is a perspective view of the fastener. Fig. 2 is 40 a longitudinal sectional view. Fig. 3 represents the fastener applied in position to the rear of a tie or scarf.

A represents the main frame or casing.

a is the bottom plate, usually provided with 45 holes or perforations for sewing or otherwise securing the fastener.

a' a' are the sides.

b is the top spring-plate.

C is the clamp or tongue hinged to the sides

50 a' a' at d.

c is a projection or lug attached to the

clamp C, which is acted upon by the spring-plate b.

e are ears or projections provided on the sides a' a' to secure the spring-plate b. 55 B represents the tie end.

The fastener is secured in the case of a tie or scarf to the back of the tie or scarf in some such position as shown in Fig. 3. When the tie end B is to be secured, it is passed 60 through the frame A to the proper length, the clamp or tongue C being raised, as shown in Fig. 1. When the scarf is in the proper position, the clamp C is then pressed down partially, when the spring-plate b engages the 65 lug or projection c, provided on the clamp C, and presses the said clamp C firmly down upon the soft material of the band or strap and holds it there firmly and prevents it from slipping.

70 The clamp C is somewhat cam-shaped, as shown in Fig. 2, and as a consequence any tension brought to bear on the tie end B from above would tend to more rigidly tighten it in the clamp C. The spring-plate b is secured 75 to the sides a' a' of the frame A by the ears e, or other suitable means. The lug or projection c, provided on the clamp C, is so adjusted that when the clamp C is down the spring-plate presses upon it, which in turn 80 communicates the pressure to the clamp C.

85 My fastener may also be employed for other purposes than securing the tie end of a necktie or scarf, as in numerous instances where buckles are usually employed.

Having thus described my invention, what I claim, and desire to secure by Letters Patent, is—

In a fastener, a frame, A, having bottom plate, a, and sides a' a', in combination with 90 the spring-plate b, secured thereto by lugs e, and the clamp C, hinged to said side plates a' a', as described, and provided with a projection, c, adapted to engage with the under side of spring-plate b, substantially as hereinbefore set forth and described.

In witness whereof I have hereunto set my hand this 8th day of November, A. D. 1888.

JACOB L. BRALLIER.

Witnesses:

CHARLES W. BOGER,

WM. L. NEVIN.
